UNITED STATES PATENT OFFICE.

JOHN T. WILLMARSH, OF NORTHRIDGE, MASSACHUSETTS.

DIE FOR BOLT-FORGING MACHINES.

Specification of Letters Patent No. 12,735, dated April 17, 1855.

To all whom it may concern:

Be it known that I, JOHN T. WILLMARSH, of Northbridge, in the county of Worcester and State of Massachusetts, have invented 5 certain new and useful Improvements in the Dies of Machines for Making Bolts, of which the following is a full, clear, and exact description, reference being had to the annexed drawings, making part of this 10 specification, in which—

Figure 8 is a section of a machine in which my dies are operated. Figs. 1 to 7 will be referred to hereafter.

In the machines heretofore contrived for 15 the purpose of manufacturing bolts and other similar articles the iron has in some cases been drawn down by subjecting it to successive blows between flat horizontal surfaces, the bar being partially rotated between each blow, by which it is flattened out first in one direction, then in another, and thus gradually drawn out and diminished in size. When iron is thus worked it is liable 20 to be cracked upon each side and the fibers are broken, particularly in the center of the bar every time the upper die or hammer descends; each succeeding stroke increasing instead of repairing the defects. This detracts materially from the strength of the 25 bolt or other article thus forged. In other cases when heavy iron has been forged a V shaped anvil has been employed, but this would obviously not be applicable to the forging or drawing down of smaller articles, 30 which require to be finished to an exact cylindrical form. Such articles have been drawn down by operating upon them by a series of semi-cylindrical dies in the opposite 35 faces of a hammer and anvil, the iron being carried from one die to the other, beginning with the largest and finishing with the smallest. This method is liable to several objections—1st. The process is slow and consequently expensive; 2d. There is 40 no method by which the exact amount of iron required for the shank of the bolt, can be drawn down; 3d. A sprue is formed from the iron each time the dies close, and particularly each time the iron is moved to a 45 smaller size die, which sprue is forced into the surface of the iron when it is again turned half round, and a defective surface which can never be remedied by the after hammering which it receives is the consequence. Such bolts are particularly inapplicable to the formation of screw bolts. 50

My invention differs from all these and consists in subjecting the iron to the action of tapering conical dies, at the same time that it is drawn gradually out of them, 55 by which means it is more rapidly elongated than in either of the above cases, and the injurious consequences before mentioned are entirely avoided, the whole force of the blow being expended in drawing out the iron in the direction of its length.

To enable others skilled in the art to understand my invention I will proceed to describe the manner in which I have carried it out.

In Fig. 8 is represented in section the machine in which the dies which form the subject of my present invention are operated. This machine is substantially similar to that described in Letters Patent granted 75 to me on the 16th January 1855 for "improved dies for making bolts" and I will briefly refer to its principal parts and the manner in which it operates.

B, B', is the bed piece or foundation 80 which holds the lower dies b, the upper dies b' being secured to the side pieces D, D', of a vibrating frame, the posts E, E', of which are secured to a cap piece F. This frame is pivoted at each end to the bed of the machine upon the gudgeons G and is caused to vibrate back and forth upon these gudgeons so as to bring the dies in the side pieces alternately into operation upon those in the bed pieces B, B' as follows—K is the main driving shaft which revolves in standards rising from the ends of the machine, and to which the driving pulley and the fly wheel N are secured—L, 85 are eccentrics secured to the shaft K and running in the straps M. These straps are grooved so as to slide freely up and down in the side posts E, and thus as the shaft K revolves, the upper die frame is vibrated upon its gudgeons. The dies b b' which 90 form the subject of my present invention are arranged in pairs as seen in the various figures. Figure 1 is a front view of them. Figs. 2 and 3 are vertical sections taken longitudinally through the cavity between them upon the line z, z, of Fig. 1. Fig. 4 a vertical section transverse to the cavity between them upon the line W, W, of Fig. 3. Fig. 5 is a plan of one of them.

From an inspection of these figures it will 110 be seen that when these dies are closed together the space between them (r) for a

short distance from their front face is very nearly cylindrical, and that it then flares out so as to form a tapering conical cavity, the size of the shorter diameter of the portion r , of this cavity corresponding to that of the finished bolt. This flattened or oval form is given to the dies in preference to an exact cylindrical form, that the edges of the dies when the two come together may 5 not cut the iron, and throw out a sprue at the sides, the conical portion of the die is also flattened in a similar manner, and for the same purpose. The iron which is to be drawn down by these dies has already been 10 operated upon and prepared by the dies for which Letters Patent were granted to me on the 16 January 1855 as before mentioned; these dies are seen in section in Fig. 7 of the accompanying drawings, but need not be 15 further described as they form no part of my present invention. The iron as it leaves these dies is of the form represented in Fig. 6; in this form it is submitted to the action of the dies b , b' , being inserted between 20 them as seen in Fig. 2, the portion t being made to enter the cavity g ; it is then continually rotated and gradually withdrawn until as seen in Fig. 3 the shank of the bolt is 25 formed, the iron being brought to its ultimate size at a single operation. The bolt 30

may be ultimately smoothed by the cylindrical dies y , or pointed in the dies x if required; these dies are made perfectly cylindrical and of the exact size of the finished bolt.

35

It is evident that when thus operated upon by tapering, conical dies the iron is confined at the sides at the instant it receives the blow, and is drawn out lengthwise, and is not continually flattened out in 40 opposite directions as is the case when other forms of dies are used.

40

The dies above described are equally well adapted to the purpose of drawing down any iron which requires to be reduced in 45 size, I do not therefore limit myself to their use in the manufacture of bolts alone, but intend to employ them whenever in the manufacture of iron they may be found useful.

45

What I claim as my invention and desire to secure by Letters Patent are—

The tapering, conical dies b b' constructed and operating in the manner substantially as herein described for the purpose set forth.

50

JOHN T. WILLMARTH.
